UNITED STATES PATENT OFFICE.

FREDERICK MACKINTOSH, OF SCHENECTADY, NEW YORK, ASSIGNOR TO GENERAL ELECTRIC COMPANY, A CORPORATION OF NEW YORK.

ELECTRIC FUSE.

No. 876,984.

Specification of Letters Patent.

Patented Jan. 21, 1908.

Application filed September 29, 1904. Serial No. 226,484.

To all whom it may concern:

Be it known that I, FREDERICK MACKINTOSH, a citizen of the United States, residing at Schenectady, county of Schenectady, State of New York, have invented certain new and useful Improvements in Electric Fuses, of which the following is a specification.

My invention relates to fuses for electric circuits, and its object is to provide a novel form of fuse adapted to open electric circuits of high tension efficiently and reliably.

It is well known in the art that the arc formed on opening a circuit may be blown out almost instantaneously by a blast of air. I take advantage of this fact by providing a novel form of fuse in which the fuse itself forms a portion of the containing walls of an inclosed chamber, so that when the fuse 20 blows, the rise in pressure in the inclosed chamber produced by the volatilization of the fuse metal causes a rush of air through that portion of the fuse which has blown, thereby quickly extinguishing the arc that is formed.

More specifically considered, my invention consists in employing a tubular fuse which forms a portion of the containing walls of an inclosed chamber, so that when a 30 portion of the fuse blows a rush of air into or out of the tube is produced, according as the inclosed chamber is formed outside of or within the tube.

Another feature of my invention consists 35 in supplementing the pressure produced by the volatilization of the fuse by a source of compressed air, whereby the rush of air is increased and the arc more effectually extinguished.

Another feature of my invention consists 40 in forming the tubular fuse with thickened walls for the greater portion of its length, so that its strength is thereby increased and it is enabled to stand a greater pressure.

Another feature of my invention consists 45 in providing a whistle arranged to be blown by the compressed air passing from the source outward through the tube, so as to give warning to the attendant that the fuse has blown.

Other features of my invention will appear from the following specification and accompanying drawing, which shows a cross-sectional view of a fuse arranged in accordance 55 with my invention.

In the drawing, A represents a cylindrical casing which is lined with or composed of insulating material, as shown. This casing is provided at each end with a head or cap a.

B represents a tubular fuse which extends through the casing, and the ends of which are expanded to form with the heads a substantially air-tight joints. It will be seen that the fuse is reduced in thickness near the center, as indicated at b. With this arrangement, the greater part of the fuse 60 may be made amply strong to withstand the desired pressure.

C represents an outlet from the casing by means of which connection may be made to a source of compressed air.

D D represent whistles which are placed in the ends of the tubular fuse.

The operation is as follows: When an overload comes upon the circuit in which the fuse is connected, the reduced central portion of the fuse is blown, and the pressure produced by volatilization, assisted by the pressure from the auxiliary source, produces a rush of air from the chamber outwardly through the tubular fuse and effectually extinguishes the arc which is formed when the fuse blows. Since the rush of air must always occur at the point at which the fuse melts, it always occurs at the proper point 80 for extinguishing the arc. After the fuse is blown, the whistles D D, through which air from the auxiliary source is still passing, give continuous warning to the attendant that the fuse is blown. Obviously, the location 90 of these whistles may be changed if desired.

It is not essential to my invention that a cylindrical form of fuse be employed, nor is it necessary that the fuse should be tubular; although such a form is especially adapted 95 for a compact structure. It is only essential that the fuse itself should form a portion of the inclosed walls of a substantially air-tight chamber, so that the point at which the fuse melts will be the point at which the flow of 100 air from the chamber will be produced. Accordingly, I do not desire to limit myself to the particular construction and arrangement of parts shown, but aim in the appended claims to cover all modifications 105 which are within the scope of my invention.

What I claim as new and desire to secure by Letters Patent of the United States, is:

1. In an electric cut-out, a substantially air-tight chamber, and a fuse forming a por- 110

tion of the inclosing walls thereof and exposed on its side to atmosphere.

2. In an electric cut-out, a substantially air-tight chamber, a fuse forming a portion 5 of the inclosing walls thereof, and means for connecting said chamber to a source of gaseous pressure.

3. In an electric cut-out, a substantially air-tight chamber, and a tubular fuse 10 extending through said chamber and forming a portion of the inclosing walls thereof, the inner passage of said fuse being open to atmosphere and a central portion of the fuse being reduced in thickness.

4. In an electric cut-out, a substantially 15 air-tight chamber, a tubular fuse extending through said chamber, and a connection from said chamber to a source of gaseous pressure.

5. In an electric cut-out, a substantially 20 air-tight chamber, a tubular fuse therein having its inner passage connected to atmosphere, and a connection from said chamber to a source of gaseous pressure.

6. In an electric cut-out, a piece of fuse 25 metal forming a portion of an electric circuit and normally exposed on one side to a source of gaseous pressure and on the other to atmosphere.

7. In an electric cut-out, a substantially

air-tight chamber, and a tubular fuse extending through said chamber and forming a portion of the inclosing walls thereof, the inner passage of said fuse being open to atmosphere and a central portion of the fuse being reduced in thickness. 30

8. In an electric cut-out, a substantially air-tight chamber, a tubular fuse extending through said chamber and forming a portion of the inclosing walls thereof, the inner passage of said fuse being open to atmosphere 40 and a central portion of the fuse being reduced in thickness, and means for connecting said chamber to a source of gaseous pressure. 35

9. In an electric cut-out, a substantially 45 air-tight chamber, a tubular fuse extending through said chamber, a connection between said chamber and a source of compressed air, and a whistle adapted and arranged to be blown by the passage of air from said source 50 through said tube.

In witness whereof I have hereunto set my hand this 28th day of September, 1904.

FREDERICK MACKINTOSH.
